UNITED STATES PATENT OFFICE.

JACOB LEVIN, OF SPRINGFIELD, MASSACHUSETTS.

DESIGN FOR A MACHINE FOR EXTRACTING JUICE FROM FRUIT.

54,271.

Specification for Design.

Patented Dec. 9, 1919.

Application filed July 19, 1919. Serial No. 312,104. Term of patent 14 years.

To all whom it may concern:

Be it known that I, JACOB LEVIN, a citizen of Russia, residing at Springfield, in the county of Hampden and State of Massachusetts, have invented a new, original, and ornamental Design for a Machine for Extracting Juice from Fruit, of which the following is a specification, reference being had to the accompanying drawing, forming part thereof.

Figure 1 is a front elevation of the machine for extracting juice from fruit.

Fig. 2 is a side elevation of the same and Fig. 3 is a plan view of the upper portion of said machine.

I claim:

The ornamental design for a machine for extracting juice from fruit.

In testimony whereof I have hereunto set my hand in presence of a subscribing witness.

JACOB LEVIN.

Witness:

CHARLES S. GOODING.
